(57) CLAIM

The ornamental design for an over-garment with an elevated marsupial pocket, as shown and described.

DESCRIPTION

FIG. 1 is a front elevation view of an over-garment with an elevated marsupial pocket shown in accordance with our new design, and shown worn by a person having a height of

approximately six feet two inches, said person being shown in broken line in a standing position;
FIG. 2 is a top perspective view of the over-garment with an elevated marsupial pocket shown in FIG. 1;
FIG. 3 is a bottom perspective view of the over-garment with an elevated marsupial pocket shown in FIG. 1;
FIG. 4 is a front elevation view of the over-garment with an elevated marsupial pocket shown in FIG. 1;
FIG. 5 is a rear elevation view of the over-garment with an elevated marsupial pocket shown in FIG. 1;
FIG. 6 is a left side elevation view of the over-garment with an elevated marsupial pocket shown in FIG. 1;
FIG. 7 is a right side elevation view of the over-garment with an elevated marsupial pocket shown in FIG. 1;
FIG. 8 is a top plan view of the over-garment with an elevated marsupial pocket shown in FIG. 1; and
FIG. 9 is a bottom plan view of the over-garment with an elevated marsupial pocket shown in FIG. 1;
FIG. 10 is a front elevation view of an over-garment with an elevated marsupial pocket shown in accordance with our new design, and shown worn by a person having a height of approximately six feet two inches, said person being shown in broken line in a standing position;
FIG. 11 is a top perspective view of the over-garment with an elevated marsupial pocket shown in FIG. 10;
FIG. 12 is a bottom perspective view of the over-garment with an elevated marsupial pocket shown in FIG. 10;
FIG. 13 is a front elevation view of the over-garment with an elevated marsupial pocket shown in FIG. 10;
FIG. 14 is a rear elevation view of the over-garment with an elevated marsupial pocket shown in FIG. 10;
FIG. 15 is a left side elevation view of the over-garment with an elevated marsupial pocket shown in FIG. 10;

FIG. 16 is a right side elevation view of the over-garment with an elevated marsupial pocket shown in FIG. 10;
FIG. 17 is a top plan view of the over-garment with an elevated marsupial pocket shown in FIG. 10; and
FIG. 18 is a bottom plan view of the over-garment with an elevated marsupial pocket shown in FIG. 10;
FIG. 19 is a front elevation view of an over-garment with an elevated marsupial pocket shown in accordance with our new design, and shown worn by a person having a height of approximately six feet two inches, said person being shown in broken line in a standing position;
FIG. 20 is a top perspective view of the over-garment with an elevated marsupial pocket shown in FIG. 19;
FIG. 21 is a bottom perspective view of the over-garment with an elevated marsupial pocket shown in FIG. 19;
FIG. 22 is a front elevation view of the over-garment with an elevated marsupial pocket shown in FIG. 19;
FIG. 23 is a rear elevation view of the over-garment with an elevated marsupial pocket shown in FIG. 19;
FIG. 24 is a left side elevation view of the over-garment with an elevated marsupial pocket shown in FIG. 19;
FIG. 25 is a right side elevation view of the over-garment with an elevated marsupial pocket shown in FIG. 19;
FIG. 26 is a top plan view of the over-garment with an elevated marsupial pocket shown in FIG. 19; and,
FIG. 27 is a bottom plan view of the over-garment with an elevated marsupial pocket shown in FIG. 19.

The features shown in broken lines are for the purposes of showing environmental structure and boundaries that form no part of the claimed design.
